JERVIS RALPH HARBECK, OF DETROIT, MICHIGAN, ASSIGNOR TO KEMIWELD CAN COMPANY,
OF DETROIT, MICHIGAN, A CORPORATION OF MICHIGAN.

METAL SHEET PREPARED FOR PUNCHING.

No. 909,589.

Specification of Letters Patent.

Patented Jan. 12, 1908.

Application filed May 4, 1908. Serial No. 430,700.

To all whom it may concern:

Be it known that I, JERVIS RALPH HARBECK, a citizen of the United States, and a resident of Detroit, in the county of Wayne and State of Michigan, have invented a new and Improved Metal Sheet Prepared for Punching, of which the following is a specification.

This invention relates to the manufacture of sheet metal blanks such as container heads, and its object is to so prepare a sheet of metal that blanks may be sheared therefrom with the greatest economy of material.

This invention consists in a sheet of metal formed with a stop-gage shoulder a distance from one edge, slightly greater than one half the diameter of a blank.

It further consists in a sheet having the waste material at the ends removed at such points as will prevent small chips from being sheared at the first and last strokes of the dies.

It further consists in a sheet so sheared that those portions of the sheet that are usually wasted may be utilized by cutting the same into blanks for smaller container tops.

The accompanying drawing shows a sheet of metal prepared so as to be peculiarly adapted for the cutting out of circular blanks.

Where circular blanks are cut from sheets, in parallel rows crossing each other at right angles, by means of gang punches, the waste is usually about 33 per cent. Where the blanks are cut from the sheets in parallel staggered rows as shown in the drawings, the waste is about 28 per cent. By cutting the small rectangular blanks from the portions that usually become waste, the total loss is about 24 per cent. These percentages are sometimes reduced by greater care in cutting, but the difference between the amounts of waste will remain practically the same.

If the large blanks were first punched from the sheets 10, as indicated in dotted lines, the expense of handling the extremely limber scrap would be too great to warrant the attempt to recover the material to form the small rectangular blanks shown cut out at 11, in the drawing. It is therefore desirable to cut the holes 11 before the sheet is taken to the main punching machines.

For reasons to be explained later, it is

desirable to space the dies of the main punch so that a considerable space separates each one from the next adjacent. This results in a part of the dies operating outside of the sheet at the beginning and ending of the punching operations. If the sheet is long, or if not rectangular, small slivers of sheet metal will be cut from the sheet and fall into the dies, causing dulling and breakage. To obviate this the notches 12 are cut in the edges of the sheet.

After the sheet has been prepared as shown in solid lines in the drawing, it is ready for the gang punch. The construction and operation of this punch forms no part of this present invention but is explained here to show the importance of the sheet shown as an article of manufacture. The dies of the gang punch are placed in two parallel rows, one row being one and one half steps behind the other. (See dotted circles 2 of the drawing.) This permits the lower or die members to be of full strength, which would be impossible if the two rows were as close together as the two lower transverse rows of circles. The punch is also provided with a gage-stop which is normally in line with one of the dies, but moves out of the path of the sheet sufficiently to permit the sheet to be fed one step. The relative movements are as follows. The stop-gage being at position 13, the sheet is placed with a shoulder of an opening 11 against the same as shown. The punches then come down, one row cutting the circles 1 and the second row of punches passing through the notches 12 at the lower edge of the sheet. The stop-gage then moves out of the path of the sheet, permitting the waste between the opening 11 and circle 1 to pass,

the gage at once moving into the path of the sheet so as to assume the relative position 14. The punch then operates, cutting the circles marked 2. Further operations of the punch cut the circles marked 3, 4, 5, 6 and 7 consecutively with the 3rd to 7th movements of the machine. At the 8th movement the first set of punches pass through the notches 12 at the last end of the sheet, while the second row of punches cut the circles 8, completing the cutting out of the blanks.

It will be noticed that the cutting of the openings 11 forms an abutment or shoulder for the stop-gage, that but one stop-gage is employed, and that this permits the wide

spacing of the dies of the gang punch. The cutting of the notches 12 is done with "open-bottom" dies, where there is no danger of damage from the waste trimming. The tools that cut the openings 11 may be forming dies.

While the stop-gage has been indicated as having but one finger, it is to be understood that sets of these fingers may be employed, one for each opening 11. And while circular blanks are indicated in the drawing, any desirable shape may be cut with corresponding saving of material.

Having now explained my invention, what I claim and desire to secure by Letters Patent is:

1. A new article of manufacture comprising a sheet of metal adapted for cutting out of a multiple of rows of blanks in staggered relation, said sheet having a transverse line of openings near one end spaced between the positions of the initial blanks, said end being notched at points between said openings to provide spaces for cutting dies.
2. A new article of manufacture comprising a substantially rectangular sheet of metal adapted for the cutting out of a multiple of

rows of blanks, the cuttings of adjacent rows to be staggered, said sheets having openings cut near the opposite ends, the openings at one end of the sheet being opposite spaces between openings at the opposite end, said sheet being notched along the ends between the openings, the bottoms of the notches in each end being in a straight line at right angles to the side of the sheet.

3. A new article of manufacture comprising a substantially rectangular sheet of metal adapted for the cutting out of a multiple of rows of blanks, the cuttings of adjacent rows to be staggered, said sheet having openings cut near the opposite ends, the openings at one end of the sheet being opposite spaces between openings at the opposite end, said openings of each end being in a line at right angles to the side of the sheet.

In testimony whereof, I have signed this specification in the presence of two subscribing witnesses.

JERVIS RALPH HARBECK.
